UNITED STATES PATENT OFFICE.

ALBERT A. MACLEOD, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,228,684.

Specification of Letters Patent. Patented June 5, 1917.

Application filed September 17, 1915. Serial No. 51,191.

To all whom it may concern:

Be it known that I, ALBERT A. MACLEOD, a citizen of the United States, residing at Swampscott, in the county of Essex and State of Massachusetts, have invented certain Improvements in Work-Supports, of which the following description, in connection with the accompanying drawings, is a specification, like reference characters on the drawings indicating like parts in the several figures.

This invention relates to work supports and particularly to work supports adapted for use in connection with fastening inserting machines. The invention is herein illustrated as embodied in a machine for lasting stitch-down shoes of the general type disclosed and claimed in United States Letters Patent No. 1,117,087, granted November 10, 1914, on an application of Adam H. Prenzel.

Machines of the type disclosed in said Letters Patent are adapted to wipe successive portions of a shoe upper down the side faces of a last and tuck the upper into the angle between the last and the sole margin, in which position the upper while under tension is secured exactly in final lasted position by permanent lasting fastenings which are inserted through the angle of the upper into the sole. In certain classes of work it is advantageous and desirable that the fastenings be located and clenched in a slit in the sole, the fastenings being driven through the angle of the upper and into one of the two parts into which the sole is divided by the slit. Machines of the type disclosed in said Letters Patent as heretofore constructed have not been adapted for inserting the lasting fastenings in a slit in the sole principally because there has been no provision in the work supporting parts of such machines for properly positioning the outer of the sole parts into which the sole is divided by the slit to enable the machine to operate properly in the sole slit.

One of the objects of the present invention is to provide improved shoe supporting means capable of use in machines of the type above referred to, which shoe supporting means, without sacrifice of general utility, shall have especial adaptability in the use of such machines in operating upon

shoes the soles of which are slit for the reception of the lasting fastenings.

In accordance with this object of the invention, novel shoe supporting means are herein shown and described in which the staple clenching element or anvil is offset and spaced from a shoe sole engaging face, the anvil being constructed and arranged to enter a slit in the sole of the shoe to be operated upon to clench fastenings driven in said slit into one of the two sole parts into which the sole is divided by the slit, and at the same time to provide a recess between the anvil and the sole engaging face for the reception of the other of said sole parts. By the use of the illustrated construction and arrangement, not only are the fastenings driven through one of the sole parts into which the sole is divided by the slit and properly clenched in the slit, but breaking down, marring or otherwise injuring the other of said sole parts is entirely prevented so that this part of the sole may be properly laid and the slit closed after the upper securing operations have been completed.

The embodiment of the invention herein shown and described is illustrated in its application to shoes the soles of which are provided with oblique slits starting at a point somewhat removed from the point of intersection of the edge and top faces of the sole, soles provided with such slits being commonly known in the trade as "McKay channeled" soles, and the lower of the two sole parts into which the sole is divided by the slit or "channel" being commonly termed the "channel flap" or "lip." Purely for convenience, the slit in the sole and the lower of the two parts into which the sole is divided by the slit are frequently referred to hereinafter respectively as a "channel" and a "channel flap." It is to be understood, however, that this showing and description are not intended to limit the invention since it is appreciated that the invention is applicable to use in connection with soles provided with slits differing in direction from the showing in the appended drawings or located farther from or nearer to the tread face of the sole than the slit illustrated in the drawings, and the terms "channel" and "channel flap" wherever used herein are to

be understood as used generically and, accordingly, are to be so construed.

These and other features and objects of the invention will be apparent from the following detailed description read in connection with the accompanying drawings and the various novel features of the invention will be set forth in the appended claims.

In the drawings:

10 Fig. 1 is a front elevation of a portion of the upper part of the machine;

Fig. 2 is a side elevation of the work support illustrating the manner of using the work support; and

15 Fig. 3 is a perspective view of the shoe supporting block of the work support.

The illustrated machine in which a preferred embodiment of the invention is herein shown as incorporated comprises staple forming and inserting mechanism substantially like that shown and described in United States Letters Patent No. 1,016,930, granted February 13, 1912, on an application of William H. Borden, except that the parts 20 are fitted to operate upon much finer wire than is ordinarily used in machines of this type. This mechanism is mounted in a head 2 carried upon a standard 4 and the formed staple is driven through a staple guiding 25 throat in a member 6 which also acts as a lasting tool to wipe the shoe upper down the side faces of the last and tuck it into the angle between the side faces of the last and the projecting sole margin.

30 35 As shown, the work support upon which the shoe is supported during the lasting operation is movable toward the lasting tool to effect the upper stretching and wiping operation by means of a suitable foot treadle 40 (not shown), as in the machine shown in said Letters Patent No. 1,117,087. The sole supporting face of the work support is formed upon a segmental block 10 which is provided with curved flanges 12 that are 45 received in corresponding grooves in a horizontally adjustable split block 14. The segmental block 10 is guided for adjustment in the block 14 about an axis lying in a plane corresponding to the work engaging end of 50 the lasting tool 6 when it is in its operative position and it is clamped in its different positions of angular adjustment in the split block by the clamping screw 16. In order that the block 14 may be adjusted in a horizontal plane toward and away from the lasting tool 6 to bring its staple clenching 55 surface into alignment with the staple passage in the member 6, the block 14 is carried by a split block 18 provided with dove-tailed 60 guideways in which is received the dove-tail on the lower part of the block 14, the block 14 being clamped in its different positions of horizontal adjustment by the clamping nuts 24, one of which provides a connection for 65 one end of a spring 26 which tends to main-

tain the work support in its operative position, the other end of the spring being secured to a part of the machine frame. The block 18 is mounted upon a rod 28 guided for vertical movement through a treadle connection (not shown) in guideways 30 attached to the machine frame.

In the illustrated construction the segmental shoe supporting block 10 comprises a sole engaging face 29 and a fastening clenching 75 anvil 34 spaced from the sole engaging face 29, the block 10 being so positioned relatively to the block 14 that the sole engaging face 29 is substantially parallel to the bottom work engaging face of the lasting tool 6. 80 The offset fastening clenching anvil 34 is constructed and arranged to enter a slit in the sole of a shoe to be operated upon to 85 clench fastenings and it is so arranged as to present a staple clenching surface in the line of drive of the staple. As herein shown this anvil is formed upon a cylindrical plug 36 of harder material than the block 10 and is inserted in the sole supporting face of the block 10, the plug being held 90 against rotation in the block by pins 38. The fastening clenching anvil 34, as illustrated, projects at an angle above the inclined surface 32 and transversely of the block to provide a surface at substantially 95 right angles to the line of drive of the fastening inserting mechanism and has its outer vertical face cupped to provide clenching cavities 40 to facilitate controlling the direction of clench of the legs of the staple, as 100 shown in Fig. 2, the legs of the staple being preferably clenched inwardly so that there is less possibility of their being in the way during the later sewing operations. The space beneath the overhanging portion of 105 the anvil 34 and which extends beyond its outer end is cut away as at 42 to adapt it to receive the lower of the two sole parts into which the sole is divided by the slit to prevent the flap from being broken down or 110 injured by the clamping pressure between the lasting tool and the work support during the lasting and fastening inserting operations. The walls of this recess 42 are shaped, particularly with reference to the 115 offset 34, so that it opens up the slit or channel in the sole and enables the offset staple clenching anvil to enter the channel readily and in a position which will permit the 120 staple to be clenched in the bottom of the channel.

In the use of the work support herein described, the anvil 34 enters the channel in the sole, the leaf of the slit being received in the recessed portion 42 of the sole supporting block 10 and the projecting margin of the sole being supported upon the inclined sole supporting face 32 of the block 10. Movement of the work support with the shoe thereon into position for the shoe to 130

ceive a fastening causes the projecting margin of the sole and the outturned portion of the upper to be clamped between the last-
ing tool 6 and the inclined face 32 of the
5 sole supporting block 10, in which position the anvil 34 will present its clenching cavities 40 in the line of drive of the staple through the tool 6. It will be noted that since the leaf or channel flap is located in
10 the recess 42 in the block 10 it is protected from being injured during the successive fastening inserting operations of the machine.

Having thus described my invention, what
15 I claim as new and desire to secure by Letters Patent of the United States is:

1. In a machine of the class described, a shoe support comprising a sole engaging face and a fastening clenching anvil spaced
20 from said face and constructed and arranged to enter a slit in the sole of a shoe to be operated upon to clench fastenings driven into one of the two sole parts into which the sole is divided by the slit and to provide a recess
25 between said anvil and said member for the reception of the other of said sole parts.

2. In a machine of the class described, a shoe engaging support comprising a sole engaging face and a fastening clenching anvil spaced from said member and overhanging said member, said anvil being constructed and arranged to enter a slit in the sole of a shoe to be operated upon to clench fastenings driven into one of the two sole parts
35 into which the sole is divided by said slit and to provide a recess for the reception of the other of said sole parts.

3. In a machine of the class described, a shoe support having a sole engaging face, and an offset portion spaced from said sole engaging face to provide a fastening clenching element constructed and arranged to enter a slit in the sole of a shoe to be operated upon to clench fastenings driven into
45 one of the two parts into which the sole is divided by the slit and to provide a recess

between the sole engaging face and the fastening clenching element for the reception of the other of said sole parts.

4. In a machine of the class described, a work support having a shoe sole supporting face constructed and arranged to present an offset staple clenching surface and having a channel flap receiving recess located adjacent to said offset surface. 55

5. In a machine of the class described, a work support having a shoe sole supporting face a portion of which is offset to provide a staple clenching surface adapted to enter the channel of a channeled sole, and having 60 a channel flap receiving recess adjacent to said offset portion.

6. In a machine of the class described, a shoe support having a sole engaging face and an offset staple clenching anvil adapted 65 to enter a slit in the sole of a shoe to be operated upon and having a recess adjacent to said anvil to receive one of the two sole parts into which the sole is divided by said slit, the walls of said recess being relatively 70 formed and arranged to open the slit for the entrance of said anvil to facilitate clenching a staple in the bottom of said slit.

7. In a machine of the class described, a shoe support having a recess constructed 75 and arranged to receive one of two sole parts formed by slitting the marginal portion of the sole of the shoe to be operated upon and having an offset staple clenching anvil adapted to enter said slit, said anvil being 80 cupped to control the direction of clench of the legs of a staple in said slit.

8. In a machine of the class described, a work support having a top face a portion of which is offset to provide a staple clenching 85 surface adapted to enter the channel of a channeled sole, and a portion of which lies in a lower plane to receive the channel flap.

In testimony whereof I have signed my name to this specification.

ALBERT A. MACLEOD.
